ELECTRIC HAMMER

Joseph H. Cox, Forest Hills, Pa., assignor to Westinghouse Electric & Manufacturing Company, East Pittsburgh, Pa., a corporation of Pennsylvania

Application December 23, 1938, Serial No. 247,431

6 Claims. (Cl. 172—240)

My invention relates to an electric hammer, and more specifically to an electrical system for effecting reciprocation of an armature, which armature intermittently strikes a tool such as a hammer.

It is well known to provide a motor generator set to furnish alternating current and then to use rectifiers to pass alternate half cycles through each of a pair of hammer actuating coils. Such motor generator set can be replaced by a conventional electronic inverter. In the use of such electron inverter, however, it has been necessary to use a total of four rectifiers, two in the primary circuit as inverters, and two additional in the secondary circuit to control the impulses in the coils.

In accordance with my invention, two of the rectifiers have been eliminated together with the transformer, and the hammer actuating coils have been connected directly in the primary circuit instead of in the secondary circuit, as has been done previously.

An object of my invention is to provide a simple electrical system involving a minimum number of electrical devices for operating an electric hammer by a direct-current source of potential.

Another object of my invention is to provide an electrical system for operating a reciprocating tool, such as, for example, a hammer, which system is capable of handling high currents and transmitting a large energy impulse to a hammer.

Other objects and advantages will become more apparent from a study of the following specification when considered in conjunction with the accompanying drawing, in which:

Figure 1 is a schematic diagram showing an electrical system for operating a tool, such as, for example, a hammer, in accordance with my invention; and

Fig. 2 shows two different wave forms for a controlling alternating-current source and the effect of a biasing voltage thereon.

Referring to Fig. 1, numerals 1 and 2 denote a pair of coils which are adapted to be alternately energized, thereby effecting reciprocation of an armature 3 which is located therebetween, the reciprocation of which armature effects intermittent striking of the tool 4, such as, for example, a hammer. The positive terminal of the direct-current source 5 is connected by conductor 6 to one side of each of the coils. Coil 1 is connected in series with the direct-current source 5 and an electric discharge device of the immersed electrode type 7. Coil 2 is connected in series with direct-current source 5 and a second electric

discharge device of the immersed electrode type 8. Anode 9 of discharge device 7 is connected to the other side of coil 1, and anode 10 of discharge device 8 is connected to the other terminal of coil 2. The cathodes 11 and 12 of discharge devices 7 and 8, respectively, comprise a vaporizable conductive liquid, such as mercury, and have immersed therein a high resistance starting electrode 13 and 14, respectively, which is adapted to initiate a cathode spot and effect discharge of the discharge device. Connected in parallel with the discharge device 7 is a grid controlled thermionic type electric discharge tube 15, and connected in parallel with discharge device 8 is a similar grid controlled discharge tube 16. A single-phase alternating-current generator 17, which is represented by a rotor only, as shown in the drawing, the stator (not shown) being merely a permanent magnet, has a terminal 18 which is connected to grid 19 of tube 15 through a high resistance 20. Similarly, a terminal 21 is connected to grid 22 of tube 16 through a high resistance 23. The resistance may be of the order of 500,000 ohms, and the maximum voltage of alternating-current source 17 may be of the order of 50 volts depending upon the grid characteristics of tubes 15 and 16. Alternating-current generator 17 is driven by a direct-current motor 24 through a shaft 25, which motor has a suitable field 26 and a variable resistance 27 connected in series therewith, and which motor is energized by a direct-current source of potential, such as a battery 28. A biasing voltage is given to grids 19 and 22 by direct-current source 29 and adjustable resistor 30. The positive terminal of the direct-current source 29 is connected through a portion of resistor 30 to the cathodes 11 and 12 of tubes 7 and 8, whereas the negative terminal is connected to the midpoint 31 of the coils of the alternating-current generator 17 through brush 32. The alternating-current generator 17 may be of the type which produces a sine wave, as shown in Fig. 2, or may be an impulse generator producing a wave form such as shown in the lower part of Fig. 2.

Fig. 2 shows two different wave forms which may be desirable from alternating-current generator 17, namely, a sine wave and an impulse wave, as shown. The bias voltage furnished by battery 29 and resistor 30 and its relation to the wave form are also shown.

The operation of the device is as follows: Since grids 19 and 22 are connected to the exterior terminals of the alternating-current generator 17, they will be alternately impressed with

a positive potential and when so impressed, they will effect a breakdown or discharge of the tube. When tube 15 discharges, a direct-current path is completed from the positive terminal of the direct-current source 5 through coil 1, conductor 33, discharge tube 15, ignition electrode 13 and cathode 11 of discharge device 7 to the negative terminal of direct-current source 5. The current passing through ignition electrode 13 and cathode 11 effects initiation of an arc and reduction of the resistance of the path between anode 9 and cathode 11 to such an extent that a breakdown or discharge will occur between electrodes 9 and 11, inasmuch as the direct-current source 5 constantly impresses a potential across electrodes 9 and 11. Hence a large direct-current impulse will be conducted through coil 1, thereby attracting armature 3 to the left. At the same time, commutating condenser 34, which is connected across coils 1 and 2, is charged by a relatively small current through coil 2, so that its positive terminal is next to tube 8. At the next half cycle of the alternating current, grid 22 becomes positive with respect to its cathode effecting discharge of tube 16 and similarly of discharge device 8. Hence the direct-current path is now established through the positive terminal of the direct-current source 5 through coil 2, discharge device 8 back to the negative terminal of source 5, and at the same time tubes 7 and 8 form a closed discharge path for commutating condenser 34. The condenser thus discharges from the anode 10 to cathode 12 of tube 8, and thence through tube 7 in a direction opposite to the previous current flow therethrough, thus aiding in deionizing tube 7. At this time both tube 7 and auxiliary tube 15 are extinguished and do not restrike, inasmuch as a suitable positive potential is no longer impressed on grid 19, and both main tube 7 and auxiliary tube 15 have become deionized by the commutating effect of condenser 34 thereon. Hence a large direct current is passed through coil 2, thus attracting armature 3 to the right and causing it to strike against tool or hammer 4. This alternate energization of coils 1 and 2 is continuous; hence a reciprocating motion of armature 3 will be effected which will cause an intermittent striking of the tool or hammer 4.

In view of the large current capacity of discharge devices 7 and 8, it will be seen that an armature 3 will strike tool or hammer 4 with a tremendous force, thereby making it suitable for heavy duty work. Obviously, in accordance with the broader aspects of my invention, any grid controlled thermionic tubes having sufficient current carrying capacity may be substituted for the immersed ignition electrode type of tubes 7 and 8.

Further, by suitably adjusting the speed of motor 24 and thus the frequency of the alternator 17, the number of hammer impacts per minute may be controlled at will. The adjustment is, most desirably, so made that the magnitude of impact and number of impacts per minute is just of the right value for most efficient operation.

I am, of course, aware that others particularly after having had the benefit of the teachings of my invention may devise other circuits embodying my invention for operating an electric hammer, and I, therefore, do not wish to be limited to the specific showings made in the drawing and the descriptive disclosure hereinbefore made, but wish to be limited only by the scope of the ap-

pended claims and such prior art as may be pertinent.

I claim as my invention:

1. An electric hammer comprising, in combination, a direct-current source, a coil and an armature therefor, switching means comprising an electric discharge device having a high current carrying capacity connected between said direct-current source and said coil, and operating means which alternately opens and closes said switching means thereby intermittently energizing said coil and effecting reciprocation of said armature, said operating means including a separate electric discharge device having a relatively low current carrying capacity as compared to said first mentioned discharge device comprising an anode, a cathode and grid, an alternating-current source having a terminal connected to said grid, said anode and cathode being connected in series with said coil and said direct-current source so as to form a separate and substantially low current control path.
2. An electric hammer comprising, in combination, a direct-current source, a pair of coils, an armature therefor, a switching means connected in series with one of said coils and said direct-current source, a second switching means connected in series with the other of said coils and said direct-current source, each of said switching means comprising electric discharge devices having relatively high current carrying capacity and operating means which opens said first switching means while closing the second, then opens said second switching means while closing the first, in periodic succession, thereby periodically energizing said first coil and said second coil in succession and effecting reciprocation of said armature, said operating means including a separate pair of grid controlled electric discharge devices of relatively low current carrying capacity as compared to said first mentioned discharge device, one for each of said coils thereby forming a low current carrying control path, and an alternating-current source having a terminal connected to one of said grids and another terminal connected to the other of said grids.
3. An electric hammer comprising, in combination, a direct-current source, a pair of coils, an armature therefor, a switching means connected in series with one of said coils and said direct-current source, a second switching means connected in series with the other of said coils and said direct-current source, each of said switching means comprising an electric discharge device having relatively high current carrying capacity and operating means which opens said first switching means while closing the second, then opens said second switching means while closing the first, in periodic succession, thereby periodically energizing said first coil and said second coil in succession and effecting reciprocation of said armature, said operating means including an alternating current source and a pair of electric discharge devices having relatively low current carrying capacities as compared to said first mentioned discharge devices, each comprising an anode, cathode and a grid, the anode and cathode of one of said electric discharge devices being connected in series with said direct-current source and one of said coils, the anode and cathode of the other of said electric discharge devices being connected in series with said other coil and said direct-current source, said grids being connected to opposite terminals of said alternating-current source.

4. An operating device for an electric hammer comprising, in combination, an inverter devoid of a transformer and including a direct-current source, a pair of highly inductive coils, an armature therefor, two electric discharge devices of the immersed ignition electrode type having relatively high current carrying capacities, each connected in series with one of said coils and said direct-current source, operating means which alternately effects discharge of said electric discharge devices thereby alternately energizing said coils and effecting reciprocation of said armature, said operating means including a pair of grid controlled electric discharge devices having relatively low current carrying capacities, one for each of said coils, and an alternating-current source having a terminal connected to one of said grids and another terminal connected to the other of said grids and a condenser connected across said coils which aids in deionizing said first-named discharge devices alternately.

5. An operating device for an electric hammer comprising an inverter devoid of a transformer, which includes, in combination, an inverter devoid of a transformer and including a direct-current source, a pair of highly inductive coils, an armature therefor, two electric discharge devices of the immersed ignition electrode type and having relatively high current carrying capacities, each connected in series with one of said coils and said direct-current source, operating means which alternately effects discharge of said electric discharge devices thereby alternately energizing said coils and effecting reciprocation of said armature, said operating means including a pair of electric discharge devices having relative-

ly low current carrying capacities, each comprising an anode, cathode and a grid, the anode and cathode of one of said electric discharge devices being connected in series with said direct-current source and one of said coils, the anode and cathode of the other of said electric discharge devices being connected in series with said other coil and said direct-current source, said grids being connected to opposite terminals of said alternating-current source and a condenser connected across said coils which aids in deionizing said first-named discharge devices alternately.

6. An operating device for an electric hammer comprising, in combination, an inverter devoid of a transformer and including a direct-current source, a pair of highly inductive coils, an armature therefor, a condenser connected across said coils to effect commutation therebetween, two electric discharge devices of the immersed ignition electrode type and having relatively high current carrying capacities, each connected in series with one of said coils and said direct-current source, a pair of grid controlled electric discharge devices having relatively low current carrying capacities, each connected in parallel with one of said immersed electrode type discharge devices, an alternating-current source having terminals connected to said grids thereby alternately impressing a positive potential on said grids to effect alternate ignition of said grid controlled electric discharge devices which in turn effects alternate ignition of said immersed electrode type electric discharge devices thereby effecting alternate energization of said coils and reciprocation of said armature.
